UNITED STATES PATENT OFFICE.

PERRY H. GENTZEL, OF NEWTON, MASSACHUSETTS.

THROTTLE VALVE.

1,405,833.

Specification of Letters Patent. Patented Feb. 7, 1922.

Application filed October 24, 1919. Serial No. 332,935.

To all whom it may concern:

Be it known that I, PERRY HOMER GENTZEL, a citizen of the United States, residing at Newton, in the county of Middlesex and State of Massachusetts, have invented certain new and useful Improvements in Throttle Valves, of which the following is a specification.

The object of my said invention is to provide an improved construction of throttle valve, the purpose being to provide a valve wherein the cutting or wearing on the valve proper by the opening and closing thereof will be reduced to a minimum, or practically eliminated, all as will herein-after be more fully described and claimed.

Referring to the accompanying drawings which are made a part hereof and on which similar reference characters indicate similar parts:

Figure 1 is a view chiefly in section through a valve casing embodying my said improvement, and

Figure 2 a cross section on the dotted line 2-2 in Figure 1.

In said drawings the valve casing A, steam inlet pipe B and steam pipe C leading to the engine are all of substantially a well known construction and arrangement. A poppet valve 10 preferably of monel metal is mounted on the valve rod 11 and is adapted to seat on a valve seat 12 in the casing between the pipes B and C to control the flow of steam from the boiler to the engine. Mounted on the valve rod 11 in a position to normally cover the annular chamber 13 in line with the pipe C is a monel metal sleeve 15 formed with a closed upper end and an open lower end, and with a number of perforations in the part which will be above the chamber 13 when the valve is closed. Said perforations are arranged in pairs, those of each pair being on diametrically opposite sides of the sleeve and in line with each other, so as to perfectly balance in operation. The lower edge of the lowermost holes are about one sixteenth of an inch, or just a short distance, above the upper edge of the annular chamber 13 when valve 10 is in its closed position.

In operation the valve being moved from its seat, steam passes by said valve, filling the chamber formed by the sleeve 15. A continuation of the movement, however, un- covers the first pair of perforations and permits the steam to begin to pass into the

annular chamber 13 and out through the pipe C to the engine. A further continuation of the movement of the valve stem until the perforations are all uncovered enables a full flow of steam from the supply pipe to the pipe leading to the engine. By this means the flow of steam is not only easily controlled, but the seating and unseating of the valve may be made easily, and without undue wear, or cutting.

Having thus fully described my said invention what I claim as new and desire to secure by Letters Patent, is:

1. A throttle valve for engines comprising a casing, a valve stem within the casing, a valve at one end of the stem, a cup shaped member on the stem opening toward the valve and having perforations near the bottom of the cup adapted to be closed by the casing, substantially as set forth.

2. In a valve mechanism, a unitary casing member having an entrance and an exit for fluid, said casing having a valve seat adjacent the entrance and an annular chamber adjacent the exit, a valve stem in the casing, a poppet valve thereon adapted to rest against said seat and a sleeve on the stem having an open end adjacent the poppet valve and having in its sides openings adapted to admit fluid to said annular chamber when the poppet valve is unseated, substantially as set forth.

3. In a valve mechanism, a unitary casing member having an entrance and an exit for fluid, said casing having a valve seat adjacent the entrance and an annular chamber adjacent the exit, a valve stem in the casing, a poppet valve thereon adapted to rest against said seat and a sleeve on the stem having a closed end and means adjacent the poppet valve to admit fluid to the sleeve and having in its sides a plurality of oppositely spaced openings at varying distances from its closed end adapted to admit fluid to said annular chamber in varying quantities when the poppet valve is unseated, substantially as set forth.

4. A throttle for engines comprising a casing, a poppet valve for controlling the flow of steam through said casing, a sleeve operable with the poppet valve and affording at times a housing for steam, said sleeve being provided with a plurality of pairs of perforations, each pair being on diametrically opposite sides of the sleeve, said casing formed with an annular chamber at all times

completely surrounding the sleeve and adapted to form a passage for steam from the sleeve when the perforations of the sleeve are brought into communication with the chamber, substantially as set forth.

5. A throttle valve for steam engines comprising a casing adapted to be connected to the boiler, a pipe leading to the engine, a poppet valve interposed between said pipes, a sleeve with closed top operable with the poppet valve and provided with a plurality of pairs of perforations spaced along the sleeve, those of each pair being on diametrically opposite sides of the sleeve and 10 in line with each other, said pairs of perforations being so arranged relative to the poppet valve that the pairs are brought 15

successively into communication with the pipe leading to the engine after the said poppet valve is unseated, said casing provided with an annular chamber surrounding a portion of the sleeve and in communication with the pipe leading to the engine, said chamber providing a passage for steam when the perforations in the sleeve are brought 20 into communication therewith, substantially as described.

In witness whereof, I have hereunto set my hand and seal at Boston, Massachusetts, this 2nd day of September, A. D. nineteen 25

hundred and nineteen.

PERRY H. GENTZEL. [L. s.]

Witness:

E. W. BRADFORD.
